DESCRIPTION

FIG. 1 is a front perspective view of a bottle opener in combination with a belt buckle showing my new design;

FIG. 2 is a rear perspective view thereof;

FIG. 3 is a front elevational view thereof;

FIG. 4 is a back elevational view thereof;

FIG. 5 is a top plan view thereof;

FIG. 6 is bottom plan view thereof;

FIG. 7 is a left side view thereof; and,

FIG. 8 is a right side view thereof.

The portions shown in broken lines are included for illustrative purpose only and form no part of the claimed design.
